(57) **CLAIM**

The ornamental design for a clicker ring, as shown and described.

DESCRIPTION

FIG. 1 is a front perspective view of the clicker ring showing my new design;

FIG. 2 is a front side elevational view thereof, the back side being a mirror image.

FIG. 3 is a left side elevational view thereof, the right side being a mirror image.

FIG. 4 is a top plan view thereof; and,

FIG. 5 is a bottom plan view thereof.

1 Claim, 4 Drawing Sheets
